CONSTANT FREQUENCY OSCILLATOR

Earl L. Koch, Chicago, Ill., assignor, by mesne assignments, to Earl L. Koch Holding Corporation, New York, N. Y., a corporation of New York

Application April 16, 1932, Serial No. 605,644

6 Claims. (Cl. 250—36)

This invention relates to improvements in oscillators, and is directed more particularly to constant frequency oscillators employing electronic devices having control elements outside the glass envelope such as described in applications, Serial Number 524,254, filed March 21, 1931, Serial Number 566,008, filed September 30, 1931, Serial Number 568,552, filed October 13, 1931 and Serial No. 605,645, filed April 16, 1932, and those shown and described herein.

In radio communication, it is important that a constant source of frequency be provided. This is particularly true in radio telephony because the only limit to the closeness of channel spacing is the degree of constancy of the transmitter frequency.

The present standard of constant frequency generator is the piezo-electric crystal controlled oscillator in which the frequency of the generated oscillation depends upon the physical dimensions of the crystal. This crystal is made of quartz and must be temperature controlled to maintain constant dimensions and consequently constant frequency. This type of oscillator has disadvantages in that the crystals are costly, they are subject to erratic behavior due to changes in the crystalline structure, and they are inflexible, a separate crystal of a different dimension being necessary for each desired frequency.

In frequency oscillators using the present types of three and four element vacuum tubes, the use of the principle of regeneration is carried to the point of sustained oscillation generation. Variations in frequency in such systems may be roughly divided into two classes, those occurring in the tube per se and the power supply connected thereto, and those occurring in the associated circuit or the instrumentalities therein. Variations in the circuit are due principally to changes in temperature, resulting in changes in the L, C and R constants of the circuit. By temperature controlling the instrumentalities and the connections thereto in the oscillatory circuit, or by designing the L and C constants of the circuit with opposite temperature coefficients so that the LC value is maintained over a wide range of temperature, these changes may be reduced or practically eliminated.

It is also possible to maintain the filament and plate voltages at practically constant values. However, notwithstanding the fact that all of these precautions are taken, it is found that in the type of oscillator using three and four element vacuum tubes the output frequency does vary.

The general conclusion by those skilled in this art is that changes in the grid current are responsible for the instability of this type of oscillator. Even in tubes of the high vacuum types there exist a considerable number of residual gas molecules capable of being ionized and causing the grid current to vary and give erratic results.

The plate current is generally measured in milliamperes, while the grid current is measured in terms of microamperes, therefore the grid is more susceptible to minute changes in space charge resulting from molecular collision in the tube.

In the new and improved constant frequency oscillator described herein the variations above mentioned are eliminated and the circuit, due to the use of an external grid type of tube, is greatly simplified by eliminating some of the instrumentalities heretofore used in oscillators employing vacuum tubes.

This type of oscillator gives results quite comparable to the best quartz crystal oscillators without the inherent disadvantages of the crystal such as described above, and possesses extreme flexibility in that the output frequency may be changed to some other value by changing one of the circuit components, generally the capacity of the condenser.

An object of the invention is the provision of a constant frequency oscillator having a minimum of circuit components, and hence a minimum number of points in the circuit in which variations can occur.

A further object of the invention is the provision of a constant frequency oscillator employing a vacuum tube in which the control element is not in the path of the electron stream, within the bulb thereof.

Other objects and advantages of the invention disclosed herein will be apparent to those skilled in the art.

Referring to the drawings:

Figure 1 is a diagram of one embodiment of the invention employing a vacuum tube having an outside grid or control element;

Figure 2 is an elevation, partly in section, showing a simple form of external grid tube which was successfully used as a constant frequency oscillator;

Figure 3 is a view of Figure 2 as viewed along the line 3—3;

Figure 4 is a sectional view along the line 4—4 of Figure 3;

Figure 5 is a front elevation, partly in section, of another type of external grid tube which gives

excellent results as an oscillator when used as herein disclosed;

Figure 6 is a section along the line 6—6 of Figure 5;

5 Figure 7 is a view taken along the line 7—7 of Figure 5;

Figure 8 is a front elevation of another type of external grid tube in which the plate is shielded against grid plate capacity by the presence of 10 the filament therebetween;

Figure 9 is a section along the line 9—9 of Figure 8; and

Figure 10 is a view taken along the line 10—10, Figure 8.

15 In Figure 1, an electronic device designated generally by the numeral 20, having a filament or cathode 21 and a plate or anode 22 within the envelope and a grid or control element 23 outside the envelope is connected up to function as 20 an oscillator. The filament 21 is connected to a suitable source of current 24, and the grid 23 and the plate 22 are connected together via an inductance 25, the grid 23 being connected to the inductance 25 at the point indicated by the 25 numeral 26 and the plate 22 being connected thereto at 27.

A suitable plate current supply 29 has its positive terminal connected to 28, the mid-tap of the inductance 25, and its negative terminal connected to one side of the filament 21. A variable condenser 30 is shunted across the terminals of the inductance 25 forming a "tank" circuit. A suitable by-pass condenser 31 is connected between the negative side of the filament and the wire leading to the mid-tap 28, or in parallel with the plate supply 29.

The frequency of this oscillator may be changed to different values by varying the capacity of the condenser 20.

40 It will be noted that the grid 23 is maintained at a high positive potential, even at substantially the same potential as that impressed upon the plate 22, no blocking condensers, grid leaks or "C" bias being necessary, and the absence of 45 these parts from the circuit eliminates the possibilities of variations which they could cause therein.

50 The absence of the grid from the path of the electron stream within the tube and the formation of a cloud of electrons inside the bulb wall of the tube in the area embraced by the outside grid makes it possible to operate this oscillator with the plate and the grid at substantially the same (positive) potential.

55 In this circuit a tube having the control element outside of the envelope may be used. One form of tube suitable for this purpose is shown in Figures 2, 3 and 4 in which a filament or cathode 32 is supported by members 33 and 34 which are secured in the "press" of the stem 35.

60 Connections to these members for supplying current to the filament 32 are shown at 38 and 39.

An anode or plate 36 is positioned adjacent to the cathode 32 and is carried by an extension of the wire 40 which is also supported by the press of the stem 35.

These elements are surrounded by a glass envelope 37 which is sealed to the stem 30.

70 A grid or control element 41 which snugly fits the envelope 37 is positioned substantially in line with the elements therein. The element 41 could embrace practically the entire surface of the envelope 37, but this has been found to be unnecessary. A suitable connection to the grid 41 is shown at 42.

Another form of tube suitable for use as a constant frequency oscillator is shown in Figures 5, 6 and 7, where a cathode or filament 43 of helical or any other suitable form is supported by the members 44, 45 passing through the press 5 of the stem 48 and the connections thereto are shown at 46 and 47 respectively.

An anode or plate 49 is positioned opposite to the filament 43 and is carried by the member 50 which is supported by the press of a second stem 10 51 and the connection thereto is shown at 55.

An enclosing glass envelope 52 has the stems 48 and 51 sealed thereto at opposite ends thereof with the cathode 43 and the anode 49 positioned therein oppositely.

15 A control element 53 fits snugly around the envelope 52 and a connection thereto is shown at 54.

Figures 8, 9 and 10 show another type of tube suitable for use as a constant frequency oscillator 20 in which an anode or plate 56 is carried by members 57 and 58 which are supported by the press of the stem 59. An extension 69 of the member 57 serves as a connection for the plate 56.

A cathode or filament 60 surrounds the plate 25 56 and is preferably concentric therewith. This filament is carried by members 61 and 62 and extensions 57 and 58 respectively thereof form connections to the filament. A disc 63 may be provided on the end of the member 61 as a shield 30 for the filament.

A glass envelope 64 is sealed to the stem 59 in substantially concentric relation to the plate and filament therein.

A grid or control element 65 fits snugly around the outside of the envelope 64 and a connection to this grid 65 is shown at 66.

The electronic device described in application Serial No. 605,645, filed April 16, 1932, is also readily adapted for use as a constant frequency 40 oscillator as outlined above.

It is obvious that other oscillating circuits than the one shown and described may be used with the types of electronic devices herein described and referred to without departing from the invention as recited in the appended claims.

What is claimed is:

1. In an oscillator, an electronic device including an evacuated envelope having contained therein an anode and a cathode, an electro-static control element or grid located external to said envelope, a resonating circuit comprising a tapped inductance with capacity in parallel connected directly between said anode and grid, and means including a power source for supplying a positive potential to said grid and anode with respect to said cathode through said inductance tap, also means for heating said cathode for the purpose of establishing an electron stream between said cathode and anode.

2. In an oscillator, an electronic device including a grid, anode and cathode, said anode and cathode being located within an evacuated envelope and said grid being located external to said envelope, an inductance directly connecting said grid and anode, a capacity in parallel with said inductance, said inductance having a tapped connection, a source of current supplying a positive potential to said grid and anode with respect to said cathode through said inductance tap, and a source of power for heating said cathode to cause electron emission therefrom.

3. In an oscillator, an electronic device including a container, an externally located grid and a plate and a filament located within said con- 75

tainer, means for heating said filament, a center-tapped inductance shunted with a variable capacity directly connecting said grid and plate, and a source of current for impressing a negative potential upon said filament and a positive potential upon said grid and plate through said center tap of said inductance.

4. In an oscillator, an electronic device including an evacuated container having plate and filament elements located therein and a grid element located external to said container and electronically isolated from said plate and filament elements, means for heating said filament, an inductance connected directly between said grid and plate, said inductance having a mid-tap, a capacity also connected directly between said grid and plate, and a source of current connected from said filament to the mid-tap of said inductance with positive polarity to said mid-tap.

20 5. In an oscillator, an electronic device includ-

ing an envelope having a plate and filament therein, a grid positioned around the outside of said envelope, means for heating said filament, an inductance connected to said grid and plate, said inductance having a mid-tap, a capacity also connected to said grid and plate, and a source of current connected from said filament to the mid-tap of said inductance.

6. In an oscillator, an electronic device including an envelope having a plate and filament therein, a grid positioned around the outside of said envelope, means for heating said filament, an inductance connected to said grid and plate, said inductance having a tapped connection, a variable capacitor also connected to said grid and plate, and a source of current connected from said filament to the tapped connection of said inductance.

EARL L. KOCH.
